UNITED STATES PATENT OFFICE.

ARTHUR W. SMITH, OF NEW YORK, N. Y., ASSIGNOR TO REMINGTON TYPEWRITER COMPANY, OF ILLION, NEW YORK, A CORPORATION OF NEW YORK.

TYPEWRITING MACHINE.

Application filed November 17, 1921. Serial No. 515,890.

To all whom it may concern:

Be it known that I, ARTHUR W. SMITH, citizen of the United States, and resident of the borough of Manhattan, city of New York, in the county of New York and State of New York, have invented certain new and useful Improvements in Typewriting Machines, of which the following is a specification.

10 My present invention relates to line lock mechanism for typewriting machines and its general object is to provide new and improved mechanism of the character specified. More specifically, one object of the invention 15 is to provide line lock mechanism which is controlled by the paper guiding fingers that co-operate with the platen to guide the paper in the vicinity of the printing line, said paper fingers actuating the line lock mechanism so as to prevent the types from striking 20 against them when opposite the printing point. Another object of the invention is to improve or extend the scope of the line lock mechanism disclosed and claimed in the 25 application of John H. Barr and Edwin E. Barney, Sr. No. 506,107, filed October 7, 1921.

To the above and other ends, which will hereinafter appear, my present invention consists in features of construction, combinations of devices and arrangements of parts hereinafter described and particularly pointed out in the claims.

In the accompanying drawings which illustrate the preferred form of my invention, 35 Figure 1 is a fragmentary front-to-rear vertical sectional view of a typewriting machine embodying the invention, only so much of said machine being shown as is necessary to a full understanding of said invention.

40 Figure 2 is a fragmentary perspective view of the line locking train embodying the invention.

As appears from Fig. 1 the main frame of the front strike typewriting machine illustrated comprises side plates or frames 1 which are connected at the front by a U-shaped frame 2 that encloses the keyboard of the machine, and at the rear by a cross plate (not shown). Mounted above the main 45 frame is a traveling carriage comprising parallel grooved bars 3 connected by a web or cross portion 4, the whole constituting the

inclined rear bar of the carriage, from the ends of which extend forwardly projecting end bars or plates 5. The grooved bars 3 provide seats for sets of anti-friction rollers 6, the upper set co-operating with a grooved seat formed in a stationary guide bar 7 which extends crosswise of the machine and is rigidly secured to the upper end portion 60 of a bed plate 8 fixed to the frame plates 1 and having a forwardly extending horizontal portion terminating in an upward extension 9 formed with a grooved seat which receives the lower set of rollers 6. On the 65 traveling carriage is a roller platen 10 with whose front face co-operate type bars 11 which are horizontally disposed in an arc below the platen and may rest normally on a padded support 12, the type bars each 70 carrying an upper case and a lower case type and being pivoted on a common pivot wire 13 mounted on a type bar support or segment 14. Each type bar has an inclined slot 15 which is engaged by a pin 16 projecting laterally from a bell crank 17, which is one of a set pivoted on a wire 18, mounted on the support 12. Links 19 connect the bell cranks 17 with angular levers 20 pivoted at 21 in a sub-frame 22 which is detachably 80 secured to the main frame. Each lever 20 carries a pin 23 which engages in a slot 24 formed in the rear of a key lever 25, the set of key levers extending forward and being pivoted on fulcrum rods 26 mounted in the 85 sub-frame 22. Each key lever is provided with a key 27 which, when depressed, will operate through the described train of devices to swing the connected type bar into printing contact with the front face of the platen 90 and the paper thereon. Mounted on the carriage is a feed rack 28 which intermeshes with a feed pinion 29 supported on a horizontal shaft 30 which takes bearings on the bed plate 8. Fixed to said shaft is an escape wheel 31 provided with radial teeth and which carries a pawl (not shown) that normally meshes with the feed pinion 29 so as to transmit feeding movements from the carriage and its rack 28 to the escape wheel 31. The carriage is power driven, being constantly urged leftward by a motor or spring drum which may be of the character shown in the aforesaid application 95 100

Sr. No. 506,107. The escapement wheel 31 co-operates with escapement devices which may be and preferably are of the character disclosed in the pending application of A. W. Smith, Sr. No. 476,788, filed June 11, 1921, the same comprising three dogs which are mounted on a two-part rocker that is vibrated when one of the printing keys is actuated so that two of the dogs will co-
10 operate with the escapement wheel to cause a no-drop letter feeding movement of the carriage during the return stroke of the actuated printing key; while the third dog is only brought into use during the actuation
15 of the space key or bar and causes a full drop or "reverse" feeding movement of the carriage. Said dog rocker comprises a main rocker part 34 and a secondary part 35 pivoted at 36 to the main part, the rocker as a
20 whole being provided with stationary pivots 37 which co-operate with depressions at the sides of the part 34, said pivots being supported on arms 38 depending from the bed plate 8. Rigid with the rocker part 34
25 is a holding dog 39 normally lying forward of the plane of the escapement wheel. A stepping dog 40 which normally engages with the lowermost tooth of the escapement wheel is pivotally supported on the rocker
30 part 35 to which is also pivoted a third dog 43 provided near its upper end with an engaging portion or tooth 43^a, which third dog is operatively controlled only from the space bar. The two-part dog rocker is provided
35 with a restoring spring 44 which maintains it normally in the Fig. 1 position and also holds the carrier parts in normal relationship.

In the present instance movement from
40 the printing keys is transmitted to the dog rocker through contact faces 11^a on the type bars which faces co-operate with the front face of a curved universal bar 45 partly housed in a seat 46 in the rear of the segment 14, and comprised in a frame which further includes an arm 52 extending rearward from the lower middle portion of the universal bar and carrying a contact device 53 which is adapted to engage with the
50 point of a contact screw 54. The universal bar frame is movably mounted on a bracket member 61 on which the type bar segment 14 is also supported, said universal bar frame being adapted for movement fore-
55 and-aft of the machine under actuation of the type bars; and also being adapted to be shifted when the type bar segment is shifted to change case, so that the front edge of the universal bar proper is always in position normally to receive actuations from the type bars. The universal bar frame is provided with a restoring spring 62 which normally maintains the universal bar in contact with the front wall of the depression 46. When one of the printing keys 27

is depressed it acts through the train of type bar actuating devices to swing the associate type bar to operative position, causing the contact face 11^a of said type bar acting against the curved universal bar 45 to move 70 the universal bar frame rearward against the pull of its spring, the movement being transmitted through the contact screw 54, to the dog rocker 34, 35, which will be swung rearward, causing the stepping dog 75 40 to disengage from the tooth of the escapement wheel and swing on its individual pivot behind said tooth, and causing the holding dog 39 to engage with said wheel tooth so that when the actuated key 27 is 80 released and the parts returned to normal position, the carriage will be permitted to step one letter space toward the left under the pull of its spring drum. The escapement is adapted to be actuated from the 85 space key or bar 63 of the machine without affecting the main dog rocker part 34. Said space bar is carried by a pair of lever arms 64 which extend forward from a rock shaft 65 having stationary bearings. Projecting 90 rearward from said rock shaft is a curved arm 66 terminating in a head 67 which normally underlies the forward arm of a lever 68 mounted on a stationary pivot 69, the forward arm of said lever terminating in 95 a stop face 68^a and the rearwardly extending arm being adapted to contact with a shoulder on an arm 71 pivotally connected to the secondary carrier part 35. The construction is such that when the 100 space key is depressed the curved arm 66 will be swung upward causing the head 67 to actuate the lever 68, the rear arm of said lever co-operating with the arm 71 to swing down the secondary carrier part 35 on its 105 pivot 36. The down swing of said part 35 causes the stepping dog 40 to disengage from the escapement wheel and brings the tooth 43^a of the third dog down into engagement therewith, the teeth of the escapement wheel being off-set rearward sufficiently to provide engaging surfaces for the dog tooth 43^a. The construction is such that the escapement operation movement is effected during the depression of the space 110 bar, the carriage movement taking place prior to the beginning of the return of the parts to normal position following the release of said space bar.

The paper feeding devices of the machine 115 comprise feed rollers (not shown) for guiding the paper at the under side of the platen, and other devices for controlling and guiding the paper at the front side of the platen at and near the printing line. The latter 120 devices comprise a pair of paper guiding members or fingers which are mounted on the carriage and adjustable lengthwise of the platen, the left-hand one of said fingers or paper guiding devices being illustrated 125 130

herein and designated as a whole by the numeral 72. Said finger is a unitary contrivance and may be made of sheet metal comprising an upright portion 73 and an integral horizontally disposed portion 74 at right angles thereto. The finger portion proper 73 extends crosswise of the printing line and is provided at its upper end with a pressure roll 75. The horizontal portion 74 is provided at its lower side in line with the finger portion 73 with a downwardly and rearwardly inclined extension or contact device 76. Said horizontal portion is also provided near its ends with pairs of clips or engaging devices 77 which are struck from the sheet metal of the part 74 itself and fit over a rectangular supporting bar 78. The bar 78 extends lengthwise of the platen at its front side and below the printing line and the guiding devices or paper finger contrivances 72 are slidably mounted on said bar. The front face of the bar is preferably marked with a scale and the edge 74^a of the paper finger 25 operates as a pointer with said scale to indicate the position of the paper finger contrivance. Near its ends the bar 78 is provided with rearwardly extending lugs 79 that are perforated to bear on outward extensions or pins 80 projecting from the forward ends of arms 81 that are secured by headed screws 82 to the web portion 4 of the carriage. The arms 81 are angled or bent so that they extend forward under the 35 platen and have secured to their upper faces by headed screws 83 spring tongues 84 that bear at their free ends against the lugs 79, thus tending to turn the bar 78 on its pivots and maintaining the pressure roll 75 in 40 spring pressed engagement with the platen or the paper thereon above the printing line. Close to its ends the bar 78 is provided with rearwardly extending arms 85 which are adapted to engage with crank arms 86 fixed 45 to a rock shaft 87 mounted on the carriage, and which may be turned to overcome the spring members 84 and throw the paper fingers forward away from the platen surface to render them inoperative. It will 50 be understood that the paper finger contrivances 72 are so spaced apart along the supporting bar 78 as to co-operate with work-sheets at their side edge portions.

It sometimes happens that the operator 55 continues actuating the printing keys after the movement of the carriage has brought one of the paper fingers opposite the printing point, the result being that in some prior constructions actuated types instead 60 of striking against the platen have struck against the paper finger, frequently battering or otherwise injuring the type, as well as defacing the finger. My invention 65 prevents such improper operation by causing the line lock mechanism to be operated by the paper fingers themselves. In the present instance this result is accomplished by providing an operating train that is actuated by the extension 76 and is effective on certain of the elements of the line 70 lock mechanism disclosed in the aforesaid pending application of John H. Barr and Edwin E. Barney, Sr. No. 506,107. Said train comprises a swinging member or arm 75 88 comprising an upright body portion 89, an elbow or off-set 90, and a curved portion 91 terminating in a head 92 provided at its sides with oppositely inclined end portions or cams 93. The member 88 is pivoted on a shoulder screw 94 which passes through a 80 bearing opening in the upper end of the upright portion 89 and is threaded into the upper end of a U-shaped bracket 95 comprising a forward upright arm 96, a horizontal cross portion 97 and a short rear 85 upright portion 98, the horizontal portion 97 connecting the upright portions 98 and 96. The portion 98 of the bracket receives headed screws 99 which are threaded into the forward side of an inverted channel bar 90 100 which extends from side to side of the machine below the platen and is detachably secured to the side frames 1. The pivotal support 94 of the arm 88 is forward of and below the parts mounted on and movable 95 with the carriage and the bracket 95 is proportioned and arranged so that said movable parts will clear it and will not be obstructed by it. The pivot 94 is at the left of the printing point and the arm 88 extends rightward therefrom so that the head 92 is in the vertical fore-and-aft plane of the printing point. Below its pivot the member or lever 88 is provided with a downward extension or lug 89^a which engages loosely in an open-mouthed slot indicated at 101 in a lever member or bell crank 100 105 designated as a whole by the numeral 102. Said lever member comprises a short forwardly extending arm 103 which overlies the horizontal portion or bracket 95, said short arm having the slot 101 formed in its free end. Said arm 103 is provided with an upwardly extending shouldered or offset portion 104 which brings it above the 110 plane of the top of the channel bar 100, so that the long arm 105 of the bell crank 102 may extend rightward lengthwise of and above said channel bar contiguous to its 115 upper face. The bell crank 102 is provided with a downwardly extending pivot pin 106 which fits in a tubular bearing 107 rigid with the channel bar and extending downward therefrom, the channel bar being perforated in register with the opening in 120 the tubular bearing 107. The right-hand or free end of the long arm 105 carries a downwardly extending vertical pin or engaging device 108 which passes freely 125 through a slot indicated at 109 in the top 130

of the channel bar, the slot being elongated so as to afford a limited extent of back and forth movement of the pin 108 when the bell crank 102 is rotated on its pivot 106. It 5 will be understood that the head 92 is in the path of the contact devices 76 on the paper fingers so that each of said paper fingers is adapted during the to-and-fro movements of the carriage to engage with 10 the cams 93 at the sides of said head and to depress the head, swinging the arm 88 on its pivot, this swinging movement being transmitted through the connection 89, 101 to the bell crank 102, the arm 104 thereof 15 carrying the pin 108 forward from the rear to the front end of the slot 109.

The pin or engaging device 108 transmits movement to the line locking mechanism which, as stated, is preferably of the construction disclosed in the aforesaid application Sr. No. 506,107. The elements of said mechanism, which are necessary to an understanding of the present invention are illustrated herein and will be briefly described, 20 reference being had to said prior application for a fuller disclosure. Said elements include stop preventive means in the form of a controlling member 155 comprising an upright arm 156, a horizontal cross portion 25 157 having ears 158 and a curved finger or engaging portion 159. Bent off from the side of the upright arm 156 is a horizontal extension or U-shaped portion 156^a whose free end is forward of and contiguous to 30 the pin 108 which is adapted to co-operate with it. The ears 158 are perforated to bear on a rod 161 supported on a U-shaped bracket comprising a horizontal cross bar 162 having parallel forwardly extending 35 arms 163 terminating in angularly disposed ears 164 which receive securing screws 165 that are threaded into the bracket member 61, the rod 161 bearing in the bracket arms 163. The cross bar 162 has an upward extension or finger 166 which acts as a stop 40 for the member 155 and against which said member is normally maintained by a coiled spring 167 which is anchored to a pin 168 on the right-hand arm 163, the rear end of said 45 spring being hooked through a hole in a lug projecting laterally from the finger 159, the finger 159 being normally maintained by said spring in a position to sustain in inoperative position a stop 169 for the universal bar. The stop 169 is preferably in the form 50 of a U-shaped frame of sheet metal comprising a cross portion 170 having parallel side arms 171 which loosely embrace the arms 163 and are perforated to bear on the rod or 55 shaft 161. Off-set forward and leftward from the cross portion 170 is an extension 60 172 which provides an abutment or stop proper, the forward edge of said extension being adapted to co-operate with a lug 173

projecting upward from the arm 52 of the 65 universal bar frame. The extension 172 is normally held up out of the path of the lug 173, but when released by the controlling member 155 drops down through the force of gravity close behind the lug 173 so as 70 substantially to prevent movement thereof, the abutment 172 and lug 173 constituting cooperative stops to lock the universal bar against movement and the printing keys from co-operation with the platen, thus locking the line. The normal position of the parts is shown in both Figs. 1 and 2, but it will be understood that when the head 92 is depressed by one of the paper fingers, the arm 88 will be swung on its pivot and this 75 movement will be transmitted through the bell crank 102, pin 108, and U-shaped extension 156^a to the frame 155, rocking said frame on its pivotal axis 161, thereby lowering the finger 159 and permitting the abut- 80 ment 172 to drop down into the path of and contiguous to the rear face of the lug 173, thereby effectively blocking the universal bar against operative movement.

The controlling member or frame 155 is 85 also effective through the last described movement to release a gravity operated stop device for the space bar mechanism, said device in the present instance being in the form of a frame or member 174 comprising 90 a cross portion 175 having pintles 176, and also provided with a downward extension 177 near one end and near the other with an angular extension 179 terminating in a 95 curved head 180 which lies behind the arm 100 156 of the stop controller or preventer 155. The stop member 174 is hung from a bracket 105 suitably secured to the bed plate 8 and comprising a cross portion 181 having extensions 182 provided with ears 183 perforated to receive the pintles 176, the member 174 being thus suspended and normally held 110 back as shown in the drawings by the arm 156 acting against the head 180. When, however, the controller 155 is actuated as 115 described and the arm 156 swings forward the member 174 will be released and will swing forward until the finger 177 is brought to a vertical position, at which time it will lie in the path of the stop 68^a on the lever 120 68. The locking of the space bar may thus give warning that a paper finger is opposite the printing point. Moreover, it frequently happens that where a printing key line lock is employed without a space bar line lock, 125 the operator, should the line lock operate to prevent the printing of the final letter of a word, will nevertheless operate the space bar, causing the carriage to space, and will then release the line lock in order to print the final letter of a word. This printing of course will take place a letter space to the right of the proper position should the op-

erator neglect to back space the carriage before printing the final letter. The employment of the space bar line lock remedies this defect by preventing the improper 5 operation above described.

From what has been said, it will be understood that when, during movement of the carriage in either direction, either of the paper fingers 72 is brought opposite the 10 printing point, the extension or contact 76, acting against one of the cam surfaces 93, will depress the head 92 and swing the arm 88 as described, maintaining said arm and the parts controlled by it, including the 15 stops for the universal bar and for the space bar, in effective position to block or prevent operation of the type bars, thus locking the line. The space bar will also be prevented from being operated. It is 20 further to be understood that the operation of the line lock mechanism by the paper fingers as described does not effect the train of connections between said mechanism and the margin and line stops disclosed in said 25 application, Sr. No. 506,107, said train operating independently of the paper finger train. As is apparent, the paper finger line lock mechanism will operate so as to prevent the types from being actuated when 30 the paper fingers are interposed between them and the printing point on the platen.

It will be observed that by my present invention there is provided in combination with a universal bar, a lock which constantly 35 tends to move into the path of said universal bar, means normally holding said lock against such movement, and devices comprising a paper finger on the travelling carriage of the machine for rendering said 40 means inoperative; that the paper finger is effective on the universal bar lock through a train of connections comprising a head or contact device which is depressible by a contact on the paper finger itself, said head being pivotally mounted so that it may swing 45 freely up and down; that said head is supported on an arm or lever member which swings in a vertical plane and has a pin and slot connection with another lever or bell 50 crank which swings in a horizontal plane; and that said bell crank carries a device or pin which is directly effective on a frame or stop preventer by which the stop proper for the universal bar is normally maintained 55 inoperative.

No claim is made in the present case to the paper finger supporting and releasing means comprising the bar 78, lugs 79, pins 80, arms 81, springs 84, arms 85, arms 86 and shaft 60 87, as such means are the invention of Edwin E. Barney and John H. Barr and are disclosed and claimed in their application, Sr. No. 582,267, filed Aug. 16, 1922. The paper finger contrivance 72 is per se also the in-

vention of Messrs. Barney and Barr and is 65 disclosed and claimed in their aforesaid application.

Various changes may be made without departing from my invention.

What I claim as new and desire to secure 70 by Letters Patent, is:—

1. In line lock mechanism for typewriting machines, the combination of a universal bar, a lock constantly tending to move into the path of said universal bar, means 75 normally holding said lock against such movement, and devices comprising a paper finger on the traveling carriage of the machine for rendering said means inoperative.

2. In line lock mechanism for typewriting 80 machines, the combination of a universal bar, a gravity operated lock therefor, preventive means normally overcoming said line lock, a paper finger, and devices controlled by said paper finger for overcoming 85 said preventive means.

3. In a typewriting machine, the combination of a traveling carriage, a universal bar, a gravity operated lock therefor, preventive means normally overcoming said 90 lock, a paper finger on said carriage, a contact operative by said paper finger, and a train of connections between said contact and said preventive means.

4. In a typewriting machine, the combination of a traveling carriage, a universal bar, a gravity operated lock therefor, preventive means normally overcoming said 95 lock, a paper finger on said carriage, a device against which said paper finger exercises a camming effect in both directions of the carriage movement, and a train of connections between said device and said preventive means.

5. In a typewriting machine, the combination of a traveling carriage, a universal bar, a gravity operated lock therefor, preventive means normally overcoming said 100 lock, a paper finger on said carriage, said paper finger being provided with a contact, a pivoted contact depressible by the contact on said paper finger and adapted to be held depressed thereby, and a train of connections between said pivoted contact and said preventive means.

6. In a typewriting machine, the combination of a traveling carriage, type bars, line lock devices, a paper finger on said carriage, said paper finger being provided with a contact, a pivoted contact depressible by the contact on said paper finger and adapted to be held depressed thereby, and a train of connections between said pivoted contact and said line lock devices.

7. In a typewriting machine, the combination of a traveling carriage, a universal bar, a gravity operated lock therefor, preventive means normally overcoming 125

said lock; a paper finger on said carriage, a lever pivoted to swing in a vertical plane and which said paper finger is adapted to depress, and a second lever pivoted to swing 5 in a horizontal plane and having pin-and-slot connections with said first recited lever, said second lever being directly effective on said preventive means.

8. In a typewriting machine, the combination of a traveling carriage, a universal 10 bar, a gravity operated lock therefor, a spring pressed member normally overcoming said lock, a paper finger on said carriage, said paper finger being provided with a contact, a pivoted contact depressible by the contact on said paper finger and adapted to be held depressed thereby, and a train of 15 connections between said pivoted contact and said preventive means.

9. In a typewriting machine, the combination of a traveling carriage, a universal bar, a gravity operated lock therefor, preventive means normally overcoming said 20 lock, a paper finger on said carriage, a pivoted member having oppositely disposed cams against which said paper finger is adapted to act, and devices connecting said pivoted member with said preventive means.

10. In a typewriting machine, the combination of a traveling carriage, a universal 25 bar, a gravity operated lock therefor, preventive means normally overcoming said lock, a paper finger on said carriage, a pivoted member having oppositely disposed cams against which said paper finger is adapted to act, a bell crank pivotally connected with said pivoted member, and a pin or extension fixed to said bell crank and operative on said preventive means.

11. In a typewriting machine, the combination of a traveling carriage, type bars, line lock devices, a paper finger on said carriage, a pivoted member having oppositely disposed cams against which said paper finger 45 is adapted to act, a bell crank pivotally connected with said pivoted member, and a pin or extension fixed to said bell crank and operative on said line lock devices.

12. In a typewriting machine, the combination of a traveling carriage, a universal 50 bar, a gravity operated lock therefor, a spring pressed pivoted frame normally overcoming said lock, a paper finger on said carriage, a lever depressible by said paper finger, and a member interposed between said lever and said pivoted frame.

13. In a typewriting machine, the combination of a traveling carriage; a universal 60 bar; a universal bar lock; a paper finger on said carriage; operating connections between said paper finger and said lock, said connections comprising an angular lever provided with a pivot pin at its angle or bend, and also provided with an actuating device on 65 one of its arms; a channel bar detachably

supported on the frame of the machine; and a tubular bearing for said pivot pin on said channel bar.

14. In a typewriting machine, the combination of a traveling carriage; a universal 70 bar; a universal bar lock; a paper finger on said carriage; operating connections between said paper finger and said lock, said connections comprising a bell crank provided with a depending pivot pin and also provided with a depending actuating pin at the free end of one of its arms; a channel bar detachably supported on the frame of the machine and provided with a slot; and a tubular bearing depending from said channel bar, said bell crank being contiguous to the upper face of said channel bar, said tubular bearing receiving said pivot pin, and said actuating pin extending down through and being adapted to play in said slot. 85

15. In line lock mechanism for typewriting machines, the combination of a traveling carriage, a paper finger thereon, escapement devices for said carriage, a universal bar effective on said escapement devices, key operated type bars for actuating said universal bar, a lock for said universal bar, and connections between said paper finger and said lock. 90

16. In line lock mechanism for typewriting machines, the combination of a traveling carriage, a paper finger thereon, escapement devices for said carriage, a universal bar effective on said escapement devices, key operated type bars for actuating said universal 100 bar, a lock constantly tending to move into the path of said universal bar, means normally holding said lock against such movement, a contact operative by said paper finger, and connections between said contact 105 and said means.

17. In line lock mechanism for typewriting machines, the combination of a traveling carriage, a paper finger thereon, a dog rocker, a universal bar effective on said dog rocker, key actuated type bars for operating said universal bar, a lock constantly tending to move into the path of said universal bar, means normally holding said lock against such movement, and devices operative by 110 said paper finger for rendering said means inoperative.

18. In a typewriting machine, the combination of a traveling carriage, a paper finger thereon, escapement devices, a type bar operated universal bar effective on said devices, a space bar, a train of connections between said space bar and said escapement devices, gravity operated locks for said universal bar and said train of space bar connections, preventive means normally overcoming said locks, a contact operative by said paper finger, and connections between said contact and said preventive means. 125

19. An angular paper finger contrivance 130

for typewriting machines, comprising a guiding portion, and a supporting portion provided with engaging devices, said contrivance carrying a pressure roll at its upper end and being provided at its lower end with a contact device for operating line lock mechanism.

Signed at the borough of Manhattan, city

of New York, in the county of New York and State of New York, this 16th day of 10 November, A. D. 1921.

ARTHUR W. SMITH.
